UNITED STATES PATENT OFFICE.

WALTER J. BARRON, OF BROOKLYN, NEW YORK.

MACHINE FOR SEPARATING GOLD, &c.

SPECIFICATION forming part of Letters Patent No. 710,738, dated October 7, 1902.

Application filed June 15, 1900. Serial No. 20,387. (No model.)

To all whom it may concern:

Be it known that I, WALTER J. BARRON, a citizen of the United States, and a resident of the borough of Brooklyn, city of New York, in the county of Kings and State of New York, have invented certain new and useful Improvements in Machines for Separating Gold, &c., of which the following is a specification.

My invention relates to gold-separating and amalgamating machines. The gold is usually separated from the gravel or sand in which it is sometimes found by means of a sluice or trough made of boards and having its bottom lined with riffles, which with or without the help of quicksilver arrest and detain the particles of gold as they are borne along by a current of water which is made to run through the sluice. In certain gold-producing territories, such as Cape Nome, the space allotted to each operator is small, and lumber and labor are scarce and costly, so as to render it unprofitable to build a sluice, and, moreover, the season is so short that the time cannot be spared for the work of building. Moreover, if the operator should learn of a richer field elsewhere he would have to abandon the sluice and erect another at the new location or else forego working the latter.

One object of my invention is to produce a sluice which can be cheaply transported to the gold-field and at once set up and operated without the delay and expense attendant upon the construction of a fixed sluice and which shall be portable, so that when one claim is exhausted or found unprofitable the machine can be hauled away and at once put into operation upon a new claim.

Another object is to impart to the sluice by means of steam or other power a slight rocking or shaking movement, so as to cause the separation or amalgamation of the gold to take place more quickly and thoroughly than is possible in a fixed sluiceway.

My invention consists in certain features of construction and combinations of devices, all as will be more fully hereinafter set forth and particularly pointed out in the concluding claims.

In the accompanying drawings, Figure 1 is a side elevation of a gold-washing machine made in accordance with my invention. Fig. 2 is a vertical cross-section of the upper trough

or pan. Fig. 3 is a vertical longitudinal section taken about centrally of the machine, the lower part of the frame and the wheels 55 being omitted. Fig. 4 is a view of the right-hand end of the machine, the motor and certain other parts being omitted; and Fig. 5 is a vertical longitudinal section, on an enlarged scale, taken centrally of a steam-motor. 60

Throughout the several views similar parts are indicated by similar numerals of reference.

The framework comprises four corner-stanchions 1, which are rigidly united by upper, 65 middle, and lower side rails or bars 2 3 4, arranged on each side of the machine, and cross-bars 5, three of the latter connecting the rear and two connecting the front stanchions. At about their middle portions the 70 cross-bars 2 3 4 in each set are united by a strut 6. The several parts of the framework are united firmly by bolts 7, which permit the frame to be partly or wholly disassembled or "knocked down" to facilitate shipment. 75 At their lower ends the stanchions are provided with bearings 8 for axles 9 of broad wheels 10, by means of which the machine may be readily rolled from one place to another. The stanchions are inclined outwardly or diverged at their lower ends, thus imparting stability to the framework. All of the stanchions, side bars, and cross-bars are preferably made of angle-iron to render the framework sufficiently stiff to sustain the 85 moving parts without making the machine too heavy for convenient transportation. The side bars are preferably inclined from the horizontal to correspond substantially with the inclination of the several troughs or pans 90 respectively carried thereby.

The upper or left-hand ends of the top side bars 2 are prolonged beyond the stanchions at 2^a and are also provided with cross-bars 11. A hopper comprising side plates 12, cross- 95 plates 13, and corner angle-irons 14 is supported between the extensions 2^a and the cross-bars 11. An outwardly-inclined grid 15 is arranged at the inlet of the hopper to prevent large stones from entering the machine and to cause them to roll off. The lower end of the hopper opens into the head of a long inclined trough or pan 16, between the sides of which extends a sheet-metal

plate or screen 17, having perforations 18, said screen extending the entire length of the pan and resting at its side edges upon ledges or angle-irons 19, which may be screwed to the sides of the pan a short distance below their upper edges. The head of the pan is preferably closed by a cross-plate 20. Riffles 21, arranged beneath the screen, extend the whole length of the pan, and a wool 10 blanket 22 is placed upon the bottom of the pan beneath the riffles. At the tail end of the pan the sides are prolonged at 16^a, and the screen-plate 17 is also prolonged and bent or curved downwardly at 23 and backwardly 15 at 24, thus giving the plate a hook-like appearance in cross-section, this portion of the plate being unperforated. Side plates 25 are combined with the bent or overhanging portion of the plate to form a hood, which is generally designated as 26 and the purpose of which is to prevent loss or escape of gold-bearing sand from the machine as it passes out of the pan. The pan is stiffened by means of angle-irons 27, secured to the under surface of the bottom thereof at its sides and extending throughout its length. The pan is pivotally supported near each end upon swinging bails 28, whose ends are pivoted at 29 in the longitudinal bars 2 of the framework, said bars being 25 preferably given the same inclination as the pan, so that the bails may be duplicates. The angle-irons 27 are notched at 30 to pivotally engage the lower portions of the bails. By means of these bail-supports the pan may 30 be given a slight rocking or swinging movement to aid or promote the separation of the gold from the gravel.

A chute 31, Fig. 4, is arranged beneath the rounded end of the screen-plate 17 to receive the tailings from said screen and convey them away from the machine, the upper end of the chute being hooked at 32 over a horizontal arm 33 of a bracket fixed upon the framework and the lower end thereof being 45 supported by a leg 34.

The tail end of the pan 16 opens into the head of a second pan 35, which is reversely inclined or extends backwardly and downwardly between the sides of the framework 50 and is also provided with a screen 36, which has finer perforations than the screen 17 and projects into the hood 26 beneath a short plate 37, fixed in said hood and constantly overlapping the screen 36 during the endwise movements of either or both of the pans, the function of said plate 37 being to direct the gold-bearing sand onto the screen 36 as it passes down from the tail end of the first pan, and so prevent loss thereof. At its tail end 55 the screen 36 is extended and formed into a hood 38, which is similar to the hood 26 and over which the tailings from this screen escape. The pan 35 is also swung upon bails 39, which are similar to the bails 28 and are 60 hung in the middle side bars 3, which may have substantially the same inclination as the pan 35. Instead of riffles and blanket

said pan is preferably provided with amalgamating-plates 40, each of which is provided at its head with an upwardly-extending rib 70 or lip to engage hooks 41, fixed to the bottom of the pan, and at its tail end with a down-turned supporting edge 42, which may be of such height as to enable said plates to lie horizontally or to raise their tail ends higher 75 than their heads. It will be seen that by this arrangement said plates overlap one another and form steps, thus breaking the run and aiding the gold to settle.

The tail end of the pan 35 in turn empties 80 into the head of a third pan 43, which is reversely inclined to pan 35 and may be substantially parallel with the top pan 16 (the several pans having a zigzag arrangement) and which is generally constructed and fitted 85 up like the pan 35. Its screen 44 is of still finer mesh than the screen 36, and the head thereof projects into the hood 38 beneath a plate 45, arranged therein and having a similar function to the plate 37. Said pan 43 is 90 swung upon bails 46, depending from the side bars 4 of the framework, and is provided with a series of stepped amalgamating-plates 40, similar to those arranged in the pan 35. Near its tail end a portion of the bottom of 95 the pan 43 is perforated at 47 to permit the tailings from the amalgamating-plates to fall into a chute or flume 48, by which they are conveyed to the dump.

A steam-motor 49 is rigidly supported by 100 and between the inclined side bars 4 near their lower ends and preferably corresponds to the steam end of the well-known "Moore" steam-pump. The reciprocating piston-rod 50 of the motor has a pin-and-slot connection 105 to a crank-arm 51, fixed upon a transverse horizontal rock-shaft 52, suitably journaled in the framework and carrying at its outer ends cross-arms 53. Links 54 (one at each side of the machine) are pivotally connected 110 at one end to said cross-arms 53 at points just below the axis 52 and at the other end to ears 55, fixed upon the sides of the pan 43. Links 56 extend from a point above said axis 53 to a pivotal connection with ears 57, provided upon the middle pan 35 the point of connection of said links 56 being at a greater distance from the axis 53 than that of the links 54, so as to give the middle pan a greater movement, said pans preferably moving in 120 opposite directions at each stroke of the piston. The upper pan 16 is connected to the cross-arms or cranks 53 by means of links 58, which extend from the upper ends of said cross-arms to the lower ends of cross-arms 125 59, provided upon a transverse shaft 60, suitably journaled upon the framework, and links 61, which extend from the upper ends of said cross-arms to ears 62, provided upon said upper pan. By means of the cross-arms 130 59 and links 62 the pan 16 is caused to move in an opposite direction from that taken by the middle pan 35, or in the same direction as the movement of the lowest pan 43, the

movement of the top pan being, however, the greatest. If desired, the two lower pans may be caused to move in the same direction at each stroke.

5 Gravel is fed into the hopper either by hand-shoveling, by a centrifugal sand-pump, or by a belt-and-bucket elevator, together with two or three times the quantity of water for washing the gravel through the pans. The grid 10 15 separates the large stones and causes them to roll off. The mixture of gravel and water falls on top of the first screen 17, the coarser part or stones roll down and discharge over the hood 26 and into the chute 31, while the 15 finer portion of the gravel, together with the black sand, passes through the screen onto the riffles 21 and the wool blanket 22. Here the black sand and the coarser particles of gold by reason of their great specific gravity settle down in the blanket and back of the riffles, the bulk of the valuable portion of the gravel being thus retained. The material which is washed over the riffles discharges onto the second screen 36, and the coarser 20 25 portion thereof washes down along said screen and is discharged over the hood 38 into the dump, while the finer material passes through the screen and washes over the amalgamating-plates 40, whereby much of the remaining 30 35 value is retained. From the second pan the material which is washed over said amalgamating-plates falls onto the third screen 44, which is of still finer mesh, and discharges the remaining coarse particles, while the remainder passes down through the screen onto the second set of amalgamating-plates 40, thus thoroughly amalgamating the finer particles of the gold. The material is then ready 40 45 for final discharge as tailings through the screen or grid 47 and into the flume or chute 48.

During the passage of the material through the machine the steam-motor 49 gives the three pans a slight rocking or shaking movement, somewhat resembling the action of a 45 common hand-rocker. This movement causes separation and amalgamation of the gold to take place more quickly and thoroughly than is possible in any style of fixed sluice-box.

It will thus be seen that I have contrived a 50 light, portable, and compact gold-washing machine which can be readily knocked down for transportation and can be readily reassembled by anybody with ordinary ability and which can then be quickly hauled over 55 land from place to place, thus saving great expense and valuable time at the outset and enabling the work of washing out of the gold to be carried on at successive locations without loss of time or considerable expense. If 60 desired, the machine can be partially knocked down and packed on the trucks or wheels ready to be hauled over almost any kind of road, although it will be found that even a partial knocking down is generally unnecessary. Preferably the pans have flaring 65 sides, so that one may be packed within the other for transportation. The machine is

complete in itself, practically separating or screening out the coarser gravel, catching the black sand and the large particles of gold 70 in the first pan, and thoroughly amalgamating the finer gold as it passes through the other two pans, thus extracting practically all the value from the gravel. The several parts are readily removable for giving access 75 to the washed-out gold and to the amalgamating-plates, the latter also being instantly removable.

It will be observed that the pans are detachably supported upon the framework and 80 have an endwise reciprocation relatively thereto, each pan being mounted so as to move independently of the others. Each of the bails 28 may be regarded as a pair of links connected by a cross-bar at their lower ends. 85 If desired, said cross-bars may be omitted and only the link portions retained, although I prefer to use the complete bail on account of its simplicity.

Many other changes in details of construction and arrangement may be resorted to within the scope of the invention.

It will be observed that I have provided a gold-washing machine in the form of a vehicle and that said machine contains within 95 itself all of the devices necessary for performing the work required, including even the presence of a motor in or upon the vehicle, which latter feature I deem of considerable importance and advantage. The steam or 100 other motive power may be connected up with the motor from any suitable source of supply and in any desired manner.

What I claim as new, and desire to secure by Letters Patent, is—

1. A gold-washing machine comprising, in combination, an inclined trough or pan, value-retaining devices arranged therein, a screen arranged over said value-retaining devices, a reversely-inclined pan arranged below the 110 first, a hood provided at the adjoining ends of the two pans, a screen arranged in said second pan and projecting into said hood, the perforations of the second screen being finer than those of the first, and a series of amalgamating-plates arranged in said second pan.

2. A gold-washing machine comprising in combination a hopper 14 having an inclined grid 15, an inclined pan 16 beneath said hopper and having a longitudinal screen 17 supported by ledges 19 in said pan, a cross-plate 20 at the head of said pan, riffles 21 in said pan below said screen, a hood 26 at the tail of said pan, a reversely-inclined pan 35 having a screen 36 extending into said hood and having 125 amalgamating-plates 40 beneath said screen.

3. A gold-washing machine comprising in combination an inclined pan 16 having a longitudinal screen 17 supported by ledges 19 within said pan, riffles 21 in said pan below 130 the screen, a hood 26 at the tail end of said pan, a reversely-inclined pan 35 having a longitudinal screen 36 extending into said hood, amalgamating-plates 40 in said pan 35 and

below said screen, a hood 38 at the tail end of said screen 36, a pan 43 inclined reversely to the pan 35, a screen in said pan 43 extending into said hood 26, and a series of amalgamating-plates below said screen in said pan 43.

4. A gold-washing machine comprising in combination a hopper, an inclined grid 15 therein, an inclined pan 16 beneath said hopper, a screen 17 in said pan, ledges 19 supporting said screen, cross-plate 20 at the head of said pan, riffles 21 in said pan beneath said screen, a hood 26 at the tail end of said pan, a reversely-inclined pan 35 having a screen 36 and amalgamating-plates 40 therebelow, a hood 38 at the tail end of the pan 35, a pan 43 inclined reversely to the pan 35, a series of amalgamating-plates in said pan 43, perforations 47 in said pan 43, and a chute 48 leading from said pan.
5. In a gold-washing machine, the combination of an inclined reciprocable trough or

pan, a second inclined trough or pan having a screen so arranged that it may receive the material discharged from the tail end of the first pan, a hood and a plate carried by the first pan and overlapping the head of said screen.

6. In a gold-washing machine, the combination of the inclined reciprocable trough or pan 16 having at the tail end thereof a hood 26, an inclined reciprocable pan 35 beneath the pan 16, a screen 36 within the latter, and a plate 37 within the hood and overlapping said screen.

Signed at the borough of Manhattan, city of New York, in the county of New York and State of New York, this 14th day of June, A.D. 1900.
